David G. Hills, Bloomfield, Conn., assignor to Plax Corporation, Bloomfield, Conn., a corporation of Delaware

Filed Dec. 28, 1960, Ser. No. 63,373

Term of patent 14 years

(Cl. D58—8)

FIG. 1

FIG. 1 is a front elevational view of a bottle showing my new design;

FIG. 2 is a top plan view thereof;

FIG. 3 is a bottom plan view thereof.

The side not shown is the same as the side shown.

The dominant features of my design reside in the portions shown in full lines and consist essentially in the top and bottom bands having oval indentations as shown.

I claim:

The ornamental design for a bottle, substantially as shown and described.
